UNITED STATES PATENT OFFICE.

JONATHAN DICKASON, OF AGOSTA, OHIO.

DESIGN FOR A NUT-LOCKING WASHER.

SPECIFICATION forming part of Design No. 32,492, dated April 10, 1900.

Application filed March 10, 1900. Serial No. 8,229. Term of patent 7 years.

To all whom it may concern:

Be it known that I, JONATHAN DICKASON, a citizen of the United States, residing at Agosta, in the county of Marion and State of 5 Ohio, have invented and produced a new and original Design for a Nut-Locking Washer; and I do hereby declare the following to be a full, clear, and exact description of the same, reference being had to the accompanying 10 drawings, forming a part thereof.

Figure 1 of the drawings is a perspective view showing the upper side of the nut-locking washer embodying my new design; Fig. 2, a similar view showing the underside thereof.

15 The leading feature of my design, as shown in the accompanying drawings, consists of the circular disk A, having a central opening a and the two parallel incisions e, extending entirely through the disk from the edge of

the central opening in a direction outward toward the outer end of the periphery of the disk, and the downwardly-inclined lugs formed by said incisions, said lugs extending downward at an angle to the plane of the disk, the ends of the lugs being flat-sided, as shown at d. 20 25

The disk A at its outer edge or periphery has upwardly-extending fingers c, formed by the incisions f.

What I claim as new is—

The design for a nut-locking washer herein 30 shown and described.

In testimony whereof I affix my signature in presence of two witnesses.

JONATHAN DICKASON.
